JOHN H. SHAW, OF NEW HAVEN, CONNECTICUT, ASSIGNOR TO SARGENT & COMPANY,
OF NEW HAVEN, CONNECTICUT

INDICATOR DOOR CHAIN

Application filed November 10, 1928. Serial No. 318,450.

My invention relates to an indicator door chain, and more especially to a door chain in which means is provided extending to the exterior of the door on which the chain may be mounted to indicate whether or not the door is secured by means of the chain.

It is usual in hotels to provide door chains on guest rooms to prevent intrusion by hotel servants and others, and with the usual door chain the servant, or other person, may unlock the door and partly open it before he becomes aware that the door is secured by means of the chain. It is, in general, an object of this invention to provide means by which a servant or other person may readily determine from the exterior of the door whether or not the door is secured by the door chain mounted on the interior thereof.

Another object of the invention is to provide an indicator door chain in which the operation of the chain itself may not be interfered with in any way by the indicating means.

To these and other ends, the invention consists in the novel features and combination of parts to be hereinafter described and claimed.

In the drawings,

Fig. 1 is a view of a part of a door and door jamb, showing a door chain according to my invention mounted thereon;

Fig. 2 is a view of the exterior of the door shown in Fig. 1, and showing an indicating means;

Fig. 3 is a sectional view, along line 3-3 of Fig. 1; and

Fig. 4 is a sectional view, along line 4-4 of Fig. 3.

Referring to the drawings in which I have illustrated my invention by showing a preferred embodiment thereof, the reference numeral 5 indicates a door broken away for the most part on which a door plate 6 is mounted, by any suitable means, as for example screws 7. In the particular instance illustrated, the door plate is pressed out of relatively heavy sheet metal and has depending peripheral flange-like edge portions 50 which bear against the surface of the door,

thus spacing the plate from the door and providing a hollow interior.

On an adjacent part of door jamb 8, a chain plate 9 is secured by screws 10, chain plate 9 having mounted thereon a loop 11 to which is secured chain 12, the other end of chain 12 being attached to a door plate engaging member, generally designated by the reference numeral 13 and comprising a substantially elliptical plate 14 having mounted thereon a loop 15, the ends of loop 15 extending through plate 14 and through a plate 16 which is provided with a pair of oppositely disposed outwardly directed arms 17 which are spaced from plate 14 a distance 65 slightly greater than the thickness of the material of door plate 6. The ends of loop 15 are upset to secure the loop and plates 14 and 16 rigidly and permanently together.

Door plate 6 is provided with an elongated opening 18 having an enlarged end 19, through which plate 16 may be inserted, movement of member 13 along opening 18 bringing arms 17 into contact with the interior surfaces of the door plate so that if the door is opened movement of the door is limited by the length of chain 12.

The door and chain described up to this point are more or less of usual construction and it will be apparent that it is impossible for one on the exterior of the door to determine whether or not the chain is in use except by attempting to open the door.

A suitable and preferred means for indicating to one at the exterior of the door the condition of the chain on the interior thereof is shown particularly in Fig. 3 and comprises a plate 20 shaped to fit and more or less loosely mounted in the hollow interior of door plate 6, plate 20, under certain conditions to be hereinafter pointed out, being freely movable towards and away from door 5. Door 5 is provided with an opening 21 in which is received a sleeve 22 having mounted therein a button 23 having a rod 24 mounted therein and extending inwardly through opening 21 and adapted to contact with plate 20. Button 23 is normally urged outwardly by means of compression spring 25, outward movement of button 23 being limited by 100

collar 26 mounted on button shank 27, the end of the latter being upset to secure the collar thereon. Sleeve 22 is provided with an interior shoulder 28, against which spring 25 bears, shoulder 28 also cooperating with collar 26 in limiting the outward movement of button 23. Sleeve 22 may be secured to door 5 in any suitable or preferred manner, herein a plate 29 being provided having a flange 30 which is received between shoulders 31 and 32 on sleeve 22, screws 33 being provided for securing plate 29 to door 5.

When the door chain is secured, as in Fig. 3 of the drawings, the arms 17 on member 13 hold plate 20 inwardly away from door plate 6 and into engagement with rod 24. In this position plate 20 resists movement on the part of button 23 and the immovability of button 23 will indicate to one at the exterior 20 of the door that the door is secured by means of the chain. If the member 13 is withdrawn from the opening in door plate 6, plate 20 may move a considerable distance when button 23 is pressed, thereby indicating to one at the exterior of the door that the door is not secured by means of the chain.

While I have shown a preferred embodiment of my invention, it will be understood that the same is not to be limited to all the details shown, but is capable of modification and variation within the spirit of the invention and the scope of the appended claims.

What I claim is:

1. In a mechanism for securing the door 35 of a room, flexible means adapted to secure the door interiorly of the room, and means exteriorly of the room to indicate whether or not the door is secured by means of the flexible means.

2. In a mechanism for securing the door 40 of a room, flexible means, a plate, means on the end of said flexible means to detachably engage said plate, and means cooperating with said plate and extending to the exterior 45 of the room to indicate whether or not the flexible means engages the plate.

3. The combination with a door chain 50 adapted to secure the door of a room, of an indicating means adapted to extend to the exterior of the room and controlled by the position of the chain at the interior of the room.

4. The combination with a flexible element 55 adapted to be mounted interiorly of a door to secure the same, of a button adapted to be mounted exteriorly of the door, and a connection between the button and element adapted to hold the button against movement when the element secures the door.

5. In combination, a flexible element and a plate adapted to be mounted at the interior 60 of a door and in cooperation with the element to restrict the movement of the door, means on the end of said element to detachably engage said plate, and means cooperating with

said plate and element to indicate at the exterior of the door whether or not the element is in engagement with the plate.

6. The combination with a flexible element for securing the door of a room, of indicating means for indicating whether or not the door is secured by means of the element, said indicating means including a part exposed at the exterior of the door and held in one position when the element secures the door and movable into another position when the door is not secured by said element.

7. In an indicator door chain, a chain, a plate, means on the end of said chain adapted to engage the plate to secure the chain thereto, a member mounted on the plate, a button adapted to be mounted adjacent said member, and means on said button adapted to engage said member, said member being movable by the button when the door is unsecured by the chain but held immovable when the means on the end of the chain secures the chain to the plate.

8. In an indicator door chain, a chain adapted to have one end secured adjacent a door, a door plate, said plate being provided with an elongated opening, means on the end of said chain adapted to be received in said opening to secure the chain to the plate, a normally movable member mounted on said plate, said member being held against movement by said means when the latter is received in the opening in the plate, a button mounted on the exterior of the door, and means on said button extending through the door and adapted to engage said member, said last named means holding the button against movement when the door is secured by means of the chain.

9. In an indicator door chain, a chain, a hollow plate, said plate being provided with an elongated opening enlarged at one end, means on the end of said chain adapted to be inserted into said opening to secure the chain to the plate, a member mounted in the hollow interior of said plate, said member being normally freely movable in said plate but engageable by said means when inserted in the plate to be held against movement, a button mounted adjacent the plate, and means on said button extending towards the plate and adapted to engage said member, said last named means holding the button against movement when the door is secured by means of the chain.

10. In an indicator door chain, a chain, a hollow plate, said plate being provided with an elongated opening enlarged at one end, means on the end of said chain adapted to be inserted into said opening to secure the chain to the plate, a member mounted in the hollow interior of said plate, said member being normally freely movable in the plate, but engageable by said means when the latter is inserted in the plate to be held against

movement, a button mounted adjacent the plate, and means on said button extending towards and adapted to engage said member, said last named means holding the button against movement when the door is secured by means of the chain.

5 11. In a means for holding the free edge of a door from swinging away from the door jamb, a flexible member adapted to be detachably secured across the opening between the door and jamb, and releasable to permit the door to swing freely, and manually movable means at the outside of the door to indicate when said member is in operative position.

10 12. The combination with a flexible element adapted to be detachably connected across the free edge of a door of a room and to the adjacent door jamb to limit the amount the door may be opened, means without the door to indicate whether or not the door is secured by means of the flexible element, said indicating means including a part held against movement in one position of the flexible element and free to move in another position of the flexible element.

15 13. The combination with a flexible element adapted to be detachably connected across the free edge of a door of a room and to the adjacent door jamb to limit the amount the door may be opened, of a slotted element in which the end of the flexible element may be received, and means at the exterior of a room to indicate whether or not the flexible element is received in the slotted element.

20 14. A member adapted to extend across the opening between the free edge of a door and a door jamb to restrict the amount the door may be opened, and an element at the exterior of the door, said element being normally movable but being held against movement when the opening movement of the door is restricted by said member.

25 15. In a combination with a flexible element for securing the door of a room, indicating means for indicating whether or not the door is secured by means of the element, said indicating means including a part exposed at the exterior of the door, said part being resiliently held in position in one position of the element, and rigidly held in position in another position of the element.

30 16. The combination with a flexible element for securing the door of a room, of indicating means for indicating whether or not the door is secured by means of the element, said indicating means including a part exposed at the exterior of the door, said part being resiliently held in position when the door is not secured by said element, and rigidly held in position when the door is secured by said element.

35 In witness whereof, I have hereunto set my hand this seventh day of November, 1928.

JOHN H. SHAW.
